Filed Apr. 13, 1962, Ser. No. 187,236
15 Claims. (Cl. 204—79)

This invention relates to an electrolytic process for the oxidation of water-soluble organic sulfides. More particularly it relates to a process for the preparation of organic sulfoxides and sulfones by the anodic oxidation of an aqueous solution of an organic sulfide.

Heretofore sulfoxides and sulfones have been prepared by the chemical oxidation of a thioether. Thus, upon treating a thioether with nitric acid a sulfoxide is formed. Similarly, controlled oxidation of a thioether with hydrogen peroxide in a solution of either acetic acid or acetone may be used to produce a sulfoxide. By the use of stronger oxidation conditions a sulfone may be produced in like manner. Thus, substituting concentrated or fuming nitric acid for the regular nitric acid, the product of oxidation of a thioether is normally the sulfone. Other strong oxidizing agents such as permanganate, hypochlorite, etc., may be used to produce sulfones. It is understood that regular commercial practice in producing organic sulfones is to oxidize a thioether utilizing hydrogen peroxide with an appropriate catalyst.

It has long been known that it is possible by similar means to produce sulfoxides and sulfones by the controlled electrolytic oxidation of a suitable thioether. Thus Fichter and Wenk in *Chemische Berichte* 45, 1376-1383 (1912) show the electrolytic oxidation of diethyl sulfide to produce first the sulfoxide and then the sulfone. In this process the diethyl sulfide is dissolved in acetic acid with hydrochloric acid added as the electrolyte and the oxidation carried out with a platinum anode to produce the sulfoxide. The sulfoxide is then isolated and placed in water with hydrochloric acid electrolyte and the oxidation completed to the sulfone. Thus the initial electrolytic oxidation is the electrolytic analogue of the earlier controlled oxidation of the sulfide to the sulfoxide using hydrogen peroxide in acetic acid under controlled conditions. The necessity according to this process for carrying out the overall production of the sulfone in two steps with an intervening separation of the sulfoxide is highly undesirable and not economical. Accordingly, the electrolytic process for the production of sulfones has never been successful.

It has now been discovered that water-soluble organic sulfides may be oxidized directly to the sulfone by electrolytic oxidation. Suitable water-soluble organic sulfides include 2,2'-dihydroxyethylsulfide, alpha-thiophenic acid, 2-thienylacetic acid, thiodiacetic acid, thiodipropionic acid, ethylthioethanol, the water-soluble sulfides formed by reacting hydrogen sulfide with either two or more mols of an alkylene oxide as propyleneoxide, or with epichlorohydrin, or with a lactone, etc. According to the process of the instant invention a solution is prepared of the water-soluble organic sulfide, water and a suitable electrolyte and an electric current passed through the solution whereby the sulfide is oxidized to the sulfoxide or the sulfone at the anode. Water-solubility is generally imparted to organic compounds by the presence of hydrophilic substituents in the compound. Such substituents are often themselves oxidizable. However, the instant process enables the thioether group to be smoothly oxidized to the sulfone with exceptionally high efficiency and a minimum of by-products without interference from such substituents.

The function of the electrolyte in the instant process is believed to be merely that of carrying current so that it is not necessary that the electrolyte form a "per" com-

2

pound. However, the precise nature of the reaction is not now known and applicant does not wish to be limited to any particular theory of operation. Suitable electrolytes include water-soluble compounds of the following anions: 5 chloride, hypochlorous, chlorate, perchlorate, fluoride, sulfate, persulfate, etc. any anion may be used which has a discharge potential greater than the oxidation potential of the organic sulfide being oxidized, but less than the oxygen overpotential on the particular anode in use. Peroxygenated intermediate anions such as persulfate are not essential as for example in the manufacture of hydrogen peroxide. The cation must form a water-soluble compound with the particular anion and desirably is selected to have a low discharge potential. The ionized salt is the electrolytic conductor and its concentration is not critical. 10 It may vary from about a fraction of 1% up to a saturated solution. Generally the presence of the organic sulfide dissolved in the water limits the solubility of the electrolyte. As is evident, the lower the concentration of electrolyte, the less the current-carrying capacity of the solution, and hence the slower the electrolytic process; the 15 larger the concentration of electrolyte, the faster the electrolytic reaction. Accordingly, the maximum concentration of electrolyte used is generally dictated solely by commercial convenience. Generally, the concentration will vary from about 0.1% by weight of the total solution up to a saturated solution of the salt.

The concentration of the water-soluble organic sulfide similarly may vary over wide limits, i.e., from about 1% 20 by weight up to the limit of solubility of the sulfide with the aqueous electrolyte solution. The minimum concentration of sulfide used will generally be limited by the depolarizing ability of the sulfide. Usually, high concentrations of organic sulfide result in decreased conductance, 25 i.e., current does not pass as readily through high concentrated sulfide solutions, so that for most efficient power use lower concentrations are sometimes desirable. Thus the maximum concentration of organic sulfide in water is imposed either by its solubility characteristics, or, in 30 cases where the sulfide is very soluble in water, by commercial consideration of efficient power use. Ordinarily, I employ solutions containing from about 30 to about 80% by weight of organic sulfide. Lower concentrations may 35 also be desirable where the sulfide might unduly limit the solubility of the electrolyte.

Electrolytic oxidation, in accordance with this invention, is ordinarily effected at about room temperature, but this is not critical and the temperature can vary over a considerable range, as from about -5° C. to about 150° C. The precise limit will vary according to the nature of the materials being oxidized. Thus the lower temperature limit is imposed by the freezing point of the solution, while the maximum operating temperature is imposed by the thermal stability of the material being oxidized. The 40 use of higher temperatures may require the use of pressurized containers to prevent escape of vapors, which in turn requires larger equipment cost. The passage of current during the electrolytic oxidation necessarily will heat the solution so that under normal operation conditions the 45 solution will normally be above room temperature. Most of the organic sulfides contemplated herein have sufficient thermal stability so that the electrolytic oxidation may proceed at the elevated temperatures encountered in such reactions without the use of extensive cooling although some cooling is desired for temperature control and lower temperatures are usually preferred. Desirable temperatures fall within the range of about 25° C. to about 90° C.

Suitable anode materials which have been used include 50 platinum, lead and carbon. In general the anode should be so selected as not to be attacked during the reaction.

The nature of the cathode is not critical. Materials such as nickel have proven eminently satisfactory without the necessity for more expensive platinum or gold.

In carrying out the process of the instant invention, the water-soluble organic sulfide is first dissolved in the desired concentration in water, along with the desired amount of electrolyte. The oxidation is then carried out at a voltage of about 2 to about 6 volts and at the maximum current density that can be used without increasing the potential to the point where undesirable by-products are formed. It has been found that a current density of about 0.02 amps./sq. cm. gives highly satisfactory results. As a result of this process there is obtained a sulf oxide or sulfone of the starting organic sulfide in high yield in a single step process without any intermediate separation and purification requirements.

The invention is illustrated, but not limited, by the following examples in which the parts are expressed by weight unless otherwise stated.

EXAMPLE I

In a glass electrolytic oxidation cell were suspended a carbon anode and a lead cathode. The cell was charged with a mixture of 37% 2,2'-dihydroxyethylsulfide, 3% sodium chloride and the balance water. The solution was anodically oxidized with direct current for 65 hours at room temperature, using 3 volts and 1 amp. As a result dihydroxyethylsulfone was formed at a cell efficiency of about 90% based upon the sulfide consumed.

In similar manner, thiadipropionic acid can be oxidized to the corresponding sulfone with high cell efficiency.

EXAMPLE II

In a glass electrolytic oxidation cell were suspended a platinum anode and a nickle cathode. The cell was charged with a mixture of 70% 2,2'-dihydroxyethylsulfide, 3% chloride and the balance water. The solution was anodically oxidized with direct current for 80 hours at ambient temperature, using 4 volts and 1 amp. As a result, dihydroxyethylsulfone was formed at a cell efficiency of over 90%, based upon the sulfide consumed.

The oxidation of Example II was repeated, using 3% solutions of each of the following electrolytes: sodium sulfate, ammonium sulfate, sulfuric acid, hydrochloric acid and arsenious acid. In each case dihydroxyethylsulfone was formed at a cell efficiency of at least about 90%, based upon the sulfide consumed.

On repeating Example II utilizing the reaction product of either propylene oxide and hydrogen sulfide or β -propiolactone and hydrogen sulfide, or epichlorohydrin and hydrogen sulfide, the corresponding sulfone is produced at high cell efficiency.

Care should be exercised in the choice of materials used for the electrolytic cell. Glass- or plastic-coated metal has been found eminently suitable.

Although the above examples illustrate a batch operation, the invention is not thus limited. The process of the instant invention is eminently suited for continuous operation and it is contemplated that the oxidation cells can be designed and arranged for continuous operation with continuous or intermittent introduction of water-soluble organic sulfide to one or a series of cells and continuous or intermittent withdrawal of the sulfone-enriched electrolyte from the cell or from one of the series of cells. Under such conditions, different operating conditions may be employed in different cells to obtain maximum current efficiency.

A process for the continuous production of dihydroxyethylsulfone is shown in the attached figure. As here shown, hydrogen and sulfur are both fed to a reactor wherein the sulfur is maintained in a molten state and the hydrogen bubbled through the sulfur at about 800° F. and 100 p.s.i. to produce hydrogen sulfide. The resulting hydrogen sulfide, together with ethylene oxide from a suitable supply, are then fed to a second reactor

where they unite and form dihydroxyethylsulfide. (By substituting propylene oxide, butylene oxide epichlorohydrin, lactones, etc., for the ethylene oxide, other suitable organic sulfides can be prepared, as known to those skilled in the art, and substituted for dihydroxyethylsulfide herein.) The resulting organic sulfide, together with an aqueous solution of a suitable electrolyte, in this case 3% sodium chloride solution (based on the total weight of the solution), are then charged to the electrolytic oxidation reactor.

This reactor constitutes a number of cells connected in series. The cells may be either bipolar or unipolar and a standard commercial design. Desirably, the last cell or cells in the series (i.e., the cells at the output end of the oxidation reactor) have substantially increased electrode areas as compared to the first cells in the series (i.e., the cells at the input end of the oxidation reactor). By increasing the electrode area, the smaller concentration of remaining sulfide can more freely contact the electrodes and there is less interference with the flow of current so that, by appropriate design, the current efficiency can be kept high throughout the reaction. Without this design it has been found that in the case of the oxidation of a 70% dihydroxyethylsulfide solution, current efficiency stays high until about 90% conversion. The final 10% conversion is attended by a marked drop-off in current efficiency and a consequent lengthening of time for the oxidation to be completed. By modifying the electrode area in the manner described, the current efficiency may be maintained high and the time for completion of the oxidation markedly reduced.

As the instant process is remarkably efficient in producing the sulfone at over 90% efficiency, the product from the last cell contains as impurities only the sodium chloride, water and no more than 10% impurities from the oxidation. This high quality product needs no further separation treatment and may be charged directly to storage as shown where it is suitable for immediate commercial use. If a more highly chemically purified product is desired, further separation as by distillation, ion exchange, etc., may be used as known to those skilled in the art.

The course of the oxidation wherein water is electrolyzed to provide the oxygen to convert the sulfide of the sulfone, produces considerable quantities of by-product hydrogen. This is taken from the electrolytic oxidation cells and recycled to the hydrogen input of the hydrogen sulfide reactor. Provision is also made in the process for the isolation of the various intermediates (i.e., mercaptoethanol and bis-hydroxyethyl sulfoxide, for the particular reactants shown) at the corresponding stages of the synthesis where it is desired to obtain such materials as commercial products. The result is a continuous process for producing an organic sulfone in high yield at extremely high efficiency.

It is contemplated that the addition of small proportions, i.e., less than about 1% by weight, of oxidation promoters to the electrolyte may be beneficial. These and similar variations in the process will, of course, be obvious to those skilled in the art.

I claim:

1. A continuous process comprising passing hydrogen and sulfur into a first reactor to form hydrogen sulfide, passing the resulting hydrogen sulfide and a 1,2-alkylene oxide to a second reactor to form a dihydroxyalkylsulfide, then passing the resulting dihydroxyalkylsulfide and an aqueous solution of an electrolyte through an electrolytic oxidation reactor wherein the dihydroxyalkylsulfide is subjected to electrolysis whereby there is obtained hydrogen and dihydroxyalkylsulfoxide, recirculating the hydrogen to the hydrogen input of the first reactor and removing the sulfoxide solution from the oxidation reactor.

2. A process for the production of an organic sulfone which comprises subjecting an aqueous solution of a

water-soluble organic thioether containing an electrolyte in an amount between about 0.1% by weight of the solution and the saturation point of the electrolyte in the solution, to direct current electrolysis at a temperature between about -5° C. and about 150° C. and a voltage between about 2 and 6 volts thereby converting said aqueous solution of a water-soluble organic thioether to an aqueous solution of the corresponding water-soluble organic sulfone.

3. A process according to claim 2 wherein the water-soluble organic thioether is dihydroxyethylsulfide.

4. A process according to claim 2 wherein the water-soluble organic thioether is the reaction product of propylene oxide and hydrogen sulfide.

5. A process according to claim 2 wherein the water-soluble organic thioether is the reaction product of hydrogen sulfide with epichlorohydrin.

6. A process according to claim 2 wherein the water-soluble organic thioether is the reaction product of hydrogen sulfide with β -propiolactone.

7. A process according to claim 2 wherein the water-soluble organic thioether is thiodiacetic acid.

8. A process according to claim 2 wherein the water-soluble organic thioether is ethylthioethanol.

9. A continuous process for the production of an organic sulfone comprising passing hydrogen and sulfur into a first reactor to form hydrogen sulfide, passing the resulting hydrogen sulfide and a 1,2-alkylene oxide to a second reactor to form a dihydroxyalkylsulfide, then passing the resulting dihydroxyalkylsulfide and an aqueous solution of an electrolyte through an electrolytic oxidation reactor wherein the dihydroxyalkylsulfide is subjected to electrolysis whereby there is obtained hydrogen and dihydroxyalkylsulfone, recirculating the hydrogen to the hydrogen input of the first reactor and removing the sulfone solution from the oxidation reactor.

10. The process according to claim 9 wherein the oxidation reactor has a plurality of cells, the cells at the output end of the reactor having substantially in-

creased electrode areas relative to the electrode areas of the cells at the input end of the reactor.

11. The process to claim 9 wherein the alkylene oxide is selected from the group consisting of ethylene oxide, propylene oxide and epichlorohydrin.

12. The process according to claim 9 wherein the alkylene oxide is ethylene oxide.

13. The process according to claim 9 wherein the temperature reactor is between 25° C. and 90° C. during the electrolysis.

14. The process according to claim 9 including means to separate the adduct of hydrogen sulfide and one mol of the 1,2-alkylene oxide from the second reactor.

15. A continuous process for the production of an organic sulfoxide and organic sulfone comprising passing hydrogen and sulfur into a first reactor to form hydrogen sulfide, passing the resulting hydrogen sulfide and a 1,2-alkylene oxide to a second reactor to form a dihydroxyalkylsulfide, then passing the resulting dihydroxyalkylsulfide and an aqueous solution of an electrolyte through an electrolytic oxidation reactor wherein the dihydroxyalkylsulfide is subject to electrolysis whereby there is obtained hydrogen, dihydroxyalkylsulfoxide and dihydroxyalkylsulfone, recirculating the hydrogen to the hydrogen input of the first reactor, removing the sulfoxide solution from a first point in the oxidation reactor and then at a subsequent point in said oxidation reactor removing the sulfone solution therefrom.
